UNITED STATES PATENT OFFICE.

FRANK NERVO, JR., OF GEYSERVILLE, CALIFORNIA.

ENGINE-PRIMER.

1,297,896.

Specification of Letters Patent. Patented Mar. 18, 1919.

Application filed August 23, 1918. Serial No. 251,177.

To all whom it may concern:

Be it known that I, FRANK NERVO, Jr., a citizen of the United States, residing at Geyserville, in the county of Sonoma and State of California, have invented new and useful Improvements in Engine-Primers, of which the following is a specification.

This invention relates to internal combustion engines, particularly to priming devices therefor, and has for its object the provision of means whereby a charge of gasoline may be allowed to flow into all the cylinders simultaneously without the operators leaving the driving seat, whereby to facilitate starting the engine in cold weather.

An important object is the provision of a device of this character including very simply and easily operated means whereby all the priming cups associated with the cylinders may be simultaneously opened and separately controlled means whereby a variable quantity of gasoline or other fuel may be admitted to the cylinders.

A further object is the provision of a device of this character which is provided with stop means whereby the operator may ascertain, without looking, whether or not the priming cups are in their open or closed positions.

An additional object is the provision of a device of this character which will be simple and inexpensive in manufacture, highly efficient in service, durable in use, easily installed and a general improvement of the art.

With the above and other objects and advantages in view, the invention consists in the details of construction to be hereinafter more fully described and claimed, and illustrated in the accompanying drawings in which:

Figure 1 is a side elevation of an internal combustion engine showing my device applied thereto.

Fig. 2 is a sectional view on the line 2—2 of Fig. 1.

Fig. 3 is a front elevation of the priming tank.

Fig. 4 is a detail elevation of one of the priming cups showing the stop member associated therewith and

Fig. 5 is a detail view of the priming cup opening treadle.

Referring more particularly to the drawings the letter A designates the front portion of an automobile and B designates a

portion of the engine provided with the usual spark plugs C extending into the cylinders thereof.

In carrying out my invention I provide a plurality of priming cups designated broadly by the letter D communicating with the cylinders of the engine. Each of these priming cups D comprises a valve body 10 provided at its lower end with a nipple 11 threaded into the cylinder head of the engine and having a valve stem 12 upon the end of which is mounted a sprocket wheel 13. A chain 14 is trained about all of the sprocket wheels 13 and extends through suitable openings in the dash E of the automobile and is trained about a sprocket 15 mounted upon a bracket 16 secured upon the front of the dash. The sprocket 15 is secured upon a shaft 17 to which is secured a treadle 18 depression of which will cause partial rotation of the shaft 17 and the sprocket 15. The shaft 17 further carries a shoe 19 which is engaged by a leaf spring 20 secured upon the dash for returning the shaft to its original position, after depression. From the above, it will be seen that depression of the pedal or treadle 18 by the operator will result in movement of the chain 14 which will turn all of the sprockets 13 and consequently open 85 the valves in the priming cups D.

In order to provide means whereby the valves in the priming cups will be opened to the proper extent, I provide upon one of the sprockets 13 an arm 21 which will engage against opposite sides of an upstanding nipple 22 formed on the priming cup body 10. Engagement of the arm 21 with this nipple will prevent further movement of the sprocket 13.

Each of the priming cups 10 is provided with the nipple 22 to which is connected by a suitable union 23 a pipe 24. All the pipes 24 extend in parallel relation to each other and extend through a suitable opening in the dash E and communicate with the bottom of a priming tank 25 suitably mounted adjacent the dash E. At the points where the pipes 24 enter the bottom of the tank 25, are formed valve seats 26 normally closed by valves 27 secured upon the lower ends of vertically extending rods 28 which extend upwardly and terminate above the top of the tank 25. The tank 25 is of course provided with a suitable filling opening closed 110 by any ordinary form of cap and is adapted to contain the gasoline or other fuel with

which the engine is to be primed. A coil spring 29 is disposed about each of the rods 28 and normally holds the valve 27 in a position to close the opening. At each end, 5 the tank 25 has secured thereon an upstanding bracket or yoke 30 which is bifurcated as shown and which is provided at one side with a plurality of teeth 31 meshing with pinions 32 secured upon the ends of a shaft 10 33 which extends through eyes 34 formed on the upper ends of the rods 28. One end of the shaft 33 is provided with a crank 34 by means of which the shaft may be rotated.

In the operation of the device, after the 15 operator has pressed upon the treadle 18 to open the priming cups, the crank 34 is grasped and turned, whereupon engagement of the pinions 32 with the teeth 31 on the brackets will cause the shaft 33 to move upwardly, pulling the rods 28 upwardly and lifting the valves 27 from the seats 26 against the resilience of the springs 29. The 20 gasoline or other fuel stored within the tank 25 will then pass through the tubes 24 and be discharged into the priming cups D from which it will pass into the cylinders of the engine. When the engine has been 25 primed, release of the crank handle 34 will permit the springs 29 to return the valves 27 to their original positions closing the openings to the pipes 24.

From the foregoing description and a 30 study of the drawings it will be apparent that I have thus provided a very simple device by means of which the cylinders of an internal combustion engine may be very quickly and easily primed to facilitate starting in cold weather or for any other desired purpose.

40 While I have shown and described the preferred embodiment of my invention, it will of course be readily understood that I reserve the right to make such changes in the form, construction and arrangements of

parts as will not depart from the spirit of 45 the invention nor the scope of the subjoined claims.

Having thus described my invention I claim:

1. A device of the character described 50 comprising in combination with an internal combustion engine, a plurality of valve priming cups communicating with the cylinders of the engine, sprockets on the valve stems of the priming cups, a stationary 55 bracket, a shaft journaled through said brackets, means for holding said shaft normally in one position, the treadle secured to said shaft, a sprocket secured upon said shaft, a chain trained about all of said 60 sprockets, movement of said treadle moving the valves of said priming cups to open position, a fuel tank, a plurality of pipes communicating with said tank and with said priming cups, and valve controlled means 65 whereby fuel may be admitted to said pipe.

2. In combination with the internal combustion engine of a motor vehicle, priming cups connected and communicating with the cylinders of the engine, means for simultaneously opening said cups, a fuel tank, a plurality of pipes communicating with said tank and with said cups, valve seats formed at the juncture of said pipes with said tanks, vertically movable spring pressed valves disposed within said tank and normally closing said pipes, a pair of brackets extending upwardly from said tank and provided with teeth, a shaft extending through said brackets and connected with said valves, pinions secured on said shaft and meshing with said teeth, and means for rotating said shaft whereby said valves may be moved upwardly.

In testimony whereof I affix my signature.

FRANK NERVO, Jr.
